(57) **CLAIM**

The ornamental design for a gaming device having multiple displays, as shown and described.

DESCRIPTION

This application relates to the following co-pending commonly owned patent applications: "Gaming Device Having Multiple Displays," Ser. No. 29/198,862, and "Gaming Device Having Multiple Displays," Ser. No. 29/198,861.

FIG. 1 is a front perspective view of a gaming device having multiple displays of my new design, that portion of the gaming device shown in phantom is not part of the design sought to be patented and is provided for environmental purposes only;

FIG. 2 is a left side elevation view of a gaming device having multiple displays of my new design illustrated in FIG. 1, the right side being a mirror image thereof; and, FIG. 3 is a top plan view of a gaming device having multiple displays of my new design illustrated in FIG. 1.
